BED SHEET

Morris B. Black, Brooklyn, N. Y.

Application March 21, 1946, Serial No. 656,010

1 Claim. (Cl. 5—334)

1

This invention relates to bed sheets and blanks for manufacturing them.

An object of the invention is to provide a bed sheet with means to retain it in stretched position about a mattress, preventing slippage and displacement of the sheet with relation to the mattress.

A further object is to provide a self-adjusting and stretching bed sheet that can be placed easily about a mattress, covering its upper face, its sides and peripheral portions of its under side.

Another object is to provide a bed sheet with pockets conveniently disposed thereon, so that contents of the pockets will be readily accessible.

Still another object is to provide a sturdy bed sheet with reenforced corners of special construction.

Another object is to provide blanks from which such sheets can be made readily in large numbers at low cost.

These and other objects are accomplished in one form of the invention by providing a bed sheet formed with a rectangular central portion, side portions laterally enclosing the central portion, two pockets opposingly disposed on the longer flaps near one end, a fold extending along the free edge of each side portion, an elastic element in the folds drawing them together, and four reenforced seams defining the corners.

For further comprehension of the invention, and of the objects and advantages thereof, reference will be had to the following description and accompanying drawings, and to the appended claim in which the various novel features of the invention are more particularly set forth.

In the accompanying drawing forming a material part of this disclosure—

Fig. 1 is a perspective view looking down on a self-stretching and adjusting bed sheet in position on a mattress.

Fig. 2 is a perspective view of the underside of the bed sheet shown in Fig. 1.

Fig. 3 is a sectional view through the line 3—3 of Fig. 1.

Fig. 4 is a fragmentary perspective detail view of a corner of the mattress with the sheet positioned thereon, the edges of the sheet being untucked.

Fig. 5 is a plan view of a blank from which a sheet similar to the sheet shown in Figs. 1 to 4 inclusive can be made.

Fig. 6 is a perspective view of a variation of the invention in position on a mattress.

Fig. 7 is a fragmentary perspective detail view of the corner of the mattress with a sheet similar

2

to the one shown in Fig. 6 positioned thereon, the edges of the sheet being untucked.

Fig. 8 is a perspective view of a corner reenforcing element of the sheet shown in Figs. 6 and 7.

Fig. 9 is a fragmentary sectional view along the line 9—9 of Fig. 6.

Fig. 10 is a plan view showing a step in the manufacture of the sheets shown in Figs. 6 and 7.

10 In the drawings and in the specification, in which like reference numbers designate similar parts, a one-piece self-stretching and adjusting bed sheet 15 shown in Figs. 1 to 4 inclusive, is positioned on a mattress 16 with a rectangular top portion 17 overlaying the top of the mattress, two long sides 18 and two short sides 19 hugging the sides and ends of the mattress, and a bottom portion 20 having a large rectangular opening 21 underlying a portion of the underside of the mattress adjacent its periphery. An elastic element 22 extends about the opening 21, resting and held within an edge fold 23 about the mouth of the opening, and tending to reduce its size. Stitches 24 extend from each corner 25 of the opening 21 to each corner 26 of the top portion 17, defining the junctions of the sides 18 and 19.

15 The bed sheet 15 can be made from a blank 27 such as is shown in Fig. 5. This blank, which is made of the usual sheeting material, is in the shape of a rectangle with square cut out corner portions, leaving two long opposite side flaps 28 and two shorter opposite end naps 29, the naps 28 and 29 each having a fold 30 along its free longitudinal edge. Adjacent nap edges 31 and 32 of the flaps 28 and 29 respectively are joined by stitches and an elastic element positioned within the folds, forming the bed sheet 15 with the stitches 24 and the elastic element 22.

20 A modified bed sheet 33, shown in Figs. 6 and 7 can be made from a blank 34 like the one shown in Fig. 10. In this variation of the invention, outside edges 35 of an L-shaped reenforcement member 36 (see Fig. 8) are secured by stitches 37 about the cut out corners of the blank 34 which is provided with two pockets 38 disposed on opposite sides thereof near one end, each pocket having an opening 39 facing toward the center of the sheet. In all other respects, the blank 34 is similar to the blank 27 heretofore described. The procedure to form the bed sheet 33 follows the same steps as those described to make the bed sheet 15, stitches 40 securing the inside edges of the reenforcement member to the 25 cut out corner edges 41 and 42 of the long flaps

43 and transverse flaps 44 respectively to form reenforced corners 45 on the bed sheet 33.

In the position of the sheet 33 on the mattress, the pockets 38 are positioned on opposite sides of the mattress 16 near one of its ends with the mouths 39 of the pockets uppermost and except for the reenforcement members and the pockets, the sheet 33 is similar in all other respects to the sheet 15.

The bed sheets 15 and 33 can be made in various sizes to fit over conventional mattresses. When positioned about a suitable mattress, the elastic element retains the sheet neatly in stretched position preventing slippage and displacement.

While I have illustrated and described the preferred embodiments of my invention, it is to be understood that I do not limit myself to the precise constructions herein disclosed and the right is reversed to all changes and modifications coming within the scope of the invention as defined in the appended claim.

Having thus described my invention, what I claim as new and desire to secure by United States Letters Patent is:

A bed sheet for covering a mattress, comprising a piece of cloth material of a size to have a center portion extend across the top of the mattress and side portions projecting beyond the periphery of the mattress, the side portions of the piece of cloth material having square cutouts cut in the corners of the sheet with the inner corners of the cutouts located at the corners of the mattress, stitches securing together the adjacent ends of the side portions of said piece of cloth material with said side portions extended at right angles to each other and at right angles to said center portion so that said side portions

can be extended downward along the sides and ends of the mattress and then inward partially along the bottom face of the mattress with the line of stitches extended downward at the corners of the mattress and radially inward at the bottom of the mattress, said side portions having their free edges folded inward forming guideways, a continuous elastic band extended through said guideways for drawing said side portions tight about the sides and ends of the mattress, and L-shaped reinforcing pieces secured to one face of said piece of cloth material at the edge portions thereof defining said square cutouts.

15 MORRIS B. BLACK.
